CLAIM

The ornamental design for a magnetic toy, as shown and described.

DESCRIPTION

FIG. 1 is a front perspective view of a magnetic toy showing our new design;

FIG. 2 is a front view of the magnetic toy shown in FIG. 1; FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a cross sectional view taken along line 8-8 of FIG. 2.

The broken lines are included for the purpose of illustrating the portions of the magnetic toy that form no part of the claimed design.
